UNITED STATES PATENT OFFICE.

STANLEY BEAUMONT EARLE, OF HORNCURCH, ENGLAND.

STROPPING OR SHARPENING APPARATUS FOR RAZOR-BLADES.

1,392,309.

Specification of Letters Patent.

Patented Oct. 4, 1921.

Application filed February 14, 1917. Serial No. 148,577.

To all whom it may concern:

Be it known that I, STANLEY BEAUMONT EARLE, a subject of His Majesty King George V of the United Kingdom of Great Britain and Ireland and of the British Dominions beyond the Sea and Emperor of India, residing at Great Nelmes, Hornchurch, Essex, England, have invented certain new and useful Improvements in Stropping or Sharpening Apparatus for Razor-Blades and the like, of which the following is a specification.

This invention has relation to razor blade and the like stropping or sharpening apparatus of the type in which the blade or implement to be stropped or sharpened is introduced between two stropping or sharpening rollers which are driven in opposite directions to act upon the presented sides 20 of the cutting edge to sharpen such edge, by a gear train of the planet-gear character, the axis of the sun-wheel being coincident with a hinging axis on which the rollers may be hinged toward and away from each 25 other while the gear wheels remain in mesh.

The present invention aims to provide a stropping or sharpening apparatus of the foregoing class which shall give notable facilities for applying a razor blade or the like thereto or removing it therefrom and which at the same time shall be of a simple, durable, and effective character; also that shall be capable of production under favorable conditions with regard to manu- 35 facturing economies.

In a stropping or sharpening apparatus according to the present invention, stropping or sharpening rolls having the gearing between them of the character hereinabove described, are provided with helical sharpening portions which bear for sharpening on non-opposite parts of the blade edge so as to tend to temporarily spring-flex the blade to a frill-like edge, 45 and the upper roll is so hinged as to rise from the appertaining side of the blade edge, and to recede therefrom in a direction away from and at right angles to the blade edge, thereby allowing a clear and unob- 50 structed drop of the blade to bring its edge on and tangent to the lower roll, guiding and positioning means of the steady pin character being provided for determining or fixing the position of the blade.

55 With such a stropping or sharpening ap-

paratus the interspacing of the roller axes in the stropping position of the rollers can be determined and controlled so as to cause the helical stropping or sharpening surfaces to exert a desired amount of pressure upon the opposite sides of the cutting edge such as to tend to temporarily spring-flex the blade to a frill-like edge, and despite the opening of the rolls to allow a clear and unobstructed drop of the blade as described, 60 the proper relative position of the helical windings for stropping is always automatically maintained by the gear wheels, as these by virtue of the rolling up which is allowed, remain in mesh and keep the rollers positively inter-controlled for preventing the original setting from becoming disturbed by the rolls becoming relatively angularly displaced on their axes while being opened or closed. 75

Thus can be realized a device, in which (a) introduction of the blade to definite stropping position, and (b) withdrawal of the blade after stropping, is notably easy with freedom from (1) risk or danger of 80 injury to either the blade or the stropping or sharpening surfaces, and (2) liability of the stropping or sharpening surfaces losing their proper relative positions for spring-flexing the blade to a frill-like edge. 85

The tangency of the pitch circles of the gear wheels being automatically preserved, controlled adjustment of the stropping or sharpening rollers is possible. Also it greatly facilitates (a) introduction of the 90 blade to definite stropping position, and (b) withdrawal of the blade after stropping.

The pressure above referred to may be rigidly or yieldingly exerted and in either case there may be a controlled adjustment 95 of the pressure as by a screw adjustment.

In the drawings:—

Figures 1 and 1^a together represent a side elevation of the blade sharpener as mounted or set at one end of a razor-containing case or box, and as viewed with the front side of the box removed, and the lid of the case or box opened to lie parallel with the base. 100

Figs. 2 and 2^a together form a view similar to Figs. 1 and 1^a but differing therefrom in the particular that whereas in Figs. 1 and 1^a the upper sharpening roller is illustrated as opened away from the blade, this upper roller is illustrated in Figs. 2 and 2^a as closed down onto the lower roller. 105 110

Fig. 3 is a plan view of Fig. 1.

Fig. 4 is a face view of a blade directing and positioning member.

Fig. 5 is a side elevation of a duplication 5 of stropping mechanism as herein described suited to strop the opposite sides of both cutting edges of a double edged blade simultaneously.

Referring to the drawings 1 and 2 designate a pair of sharpening rolls having helical sharpening portions 1^a and 2^a arranged to bear for sharpening on non-opposite parts 10 of the edge of a blade, with the object of tending to temporarily spring-flex the blade 15 to a frill-like edge. The rolls 1 and 2 are connected for drive of rotation and inter-controlled opening and closing by a toothed gear train 3, 4, 5, and 6, and are rotatably mounted in frames or carriers 7 and 8, frame 20 7 carrying the roller 1 and being mounted in a razor-containing case or box 9, and frame 8 being hinged to frame 7 on an axis which is coincident with the axis of the gear 6, this gear 6 being free on the hinging axis 25 and being driver to gear 4 and follower to gear 5, which gear 5 is in turn follower to gear 3.

The frames or carriers 7 and 8 are formed so as to allow the rollers 1 and 2 to be 30 pressed toward each other for temporarily spring-flexing the blade to a frill-like edge, and so as to allow the upper roller 2 to open away from the lower roller 1 to allow a clear and unobstructed drop of the blade to 35 bring its edge on, and tangent to the lower roll. As shown, the frames 7 and 8 are of U-shape and the upper and lower edges of their sides, which sides lie in the same vertical plane, are so sloped away from each 40 other as at 10 and 10^a that on the one hand a range of movement is given by which the frill-like edge can be imparted to the blade over a considerable variation in thickness of the stropping surfaces (see Fig. 1) whereby 45 a substantial amount of wear of the stropping surfaces is allowed for, and that on the other hand a range of separating movement or rising movement around the hinging axis is given by which the upper roller 2 can be 50 opened or raised and caused to recede in a direction away from and at right angles to the edge of the blade to leave a clear and unobstructed drop of the blade past the upper roller 2 onto the lower roller 1, (see Fig. 1). 55 When the sharpener is fully opened as depicted in Fig. 1, the center of gravity of the upper roller 2 and its hinging carrier is brought to the right of the hinging axis and the sloping edges of the two carriers 60 interact as rests or stops as at 10 for supporting the roller 2 and its carrier in the fully opened position.

The lid 11 of the case or box 9 is by preference arranged to open on a hinging 65 axis at right angles to the hinging axis of

the rolls and when the case or box 9 is closed the arrangement is made such that the lid 11 shall put pressure on the sharpener to keep the rollers to their work. Conveniently and advantageously provision of an 70 intervening spring is made, this giving softness in action or latitude in position and wear. A bow spring 12 integral or otherwise made fast with the carrier 8 as a forward medial extension thereof serves well. 75 But in place of a single spring two or more may be employed to promote evenness of bearing action on the blade edge.

Provision for directing the blade and holding it to definite position may take 80 divers forms according to the formation of the razor or blade to be directed and held. It will in this direction suffice as an example to explain directing and positioning means of a steady pin character which is appropriate to that well known razor depicted in the accompanying drawings, this razor, designated 13, being of that type in which the blade is movable from shaving relation with its guard so as to allow contact of a stropping roller on each side of the blade edge. In the particular razor illustrated the blade is movable to lie in alignment with the handle and is held in that position by a 90 spring. In the illustrated stropping position of the blade 14 and guard 15 of razor 13, a slot 16 is present: hence by the provision of an appropriately proportioned uprising pointed or inverted V-ended plate 17 having rectangular notches 18, the razor 95 may be safely directed and held by bringing the slot over the point of the plate 17 which by entering the slot guides the razor into the notches 18, the walls whereof co-act with the corresponding parts of the razor to support 100 and position this; the handle of the razor is received by a seating 19. In this way a proper and safe positioning of the blade 105 is determined or fixed.

20 designates a locking pawl for preventing rotation of the sharpening rollers 1 and 2 toward the cutting edge either by inadvertent rotation of the turning handle 21 or by any tendency of the lower roller 1 to turn during the closing down of the upper roller 115 2. In this connection the precaution may be adopted of allowing the blade to lie spring supported clear of the lower roller 1, so that the blade edge shall only be brought into contact with the sharpening portions of the 120 lower roll 1 by the pressure of the upper roller 2 as this completes its closing movement.

By preference the turning crank-handle 21 is hinged at 22 to in-fold as depicted in 125 dotted outline in Fig. 3, an opening being made in the front side of the box to allow this.

By duplication of stropping mechanism as 130 herein described stropping apparatus suited

to strop the opposite sides of both cutting edges of a double edged blade simultaneously may be provided. A convenient arrangement is illustrated by Fig. 5, this being 5 embodied as a box or frame 23 having a double folding lid 24, 25, opening from the center, each half of the box or frame 23 being fitted with stropping rollers 1, 2, with gears 3, 4, 5, and 6, arranged and operating 10 substantially as herein set forth and both pairs of stropping rollers being mounted to coöperate in receiving the opposite edges of a blade suitably supported as by a studded bracket 26 (two studs being provided for 15 engaging a pair of holes in the blade) between the two pairs of stropping rollers. In this construction the two gear trains will be suitably connected as by the gears 27, 28, for drive from a common axis, as the axis 20 of the right hand lower roller 1.

Such a duplex device may be conveniently and advantageously boxed-in (with or without spring provision such as 12) in like or similar manner to the single device above described, and for the purposes above described.

The embodiment of the invention in boxed form with a complete razor substantially as herein described gives the notable advantage

that on taking up the case or box for use 30 the blade may be sharpened or prepared by turning the handle before the case is opened.

What I claim is:—

A device for stropping razor blades comprising in combination, a pair of rolls each 35 of which is provided with an outwardly projecting spirally disposed stropping surface, the stropping surfaces between said rolls being respectively disposed between the stropping surfaces of the other roll, means mounting said rolls to permit them to be moved apart for insertion of a blade therebetween and pressed together to grip the blade with the stropping surfaces on each roll pressing the blade toward the space between the stropping surfaces of the other roll, gearing connecting said rolls and permitting them to be moved apart and positively maintained in the same angular relation when brought together, a box within which said rolls and 50 their mounting are inclosed, and a resilient device adapted upon the lid of said box being closed to urge said rolls toward one another.

In testimony whereof, I affix my signature. 55

STANLEY BEAUMONT EARLE.
